CLAIM

The ornamental design for a monitor with stand, as shown and described.

DESCRIPTION

FIG. 1 is a rear, right, top, perspective view of a monitor with stand;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines shown in the drawings represent environmental structure that forms no part of the claimed design. The "hp" lettering and icon and the "Bang & Olufsen" lettering and icon forming part of the disclosure is a registered trademark of HP Hewlett Packard Group LLC and Bang & Olufsen, respectively.
